E. OHNSTRAND

INTERFITTING CORNER CONSTRUCTION

Filed Jan. 28, 1922

UNITED STATES PATENT OFFICE.

ENOCH OHNSTRAND, OF MOHAWK, NEW YORK, ASSIGNOR TO LIBRARY BUREAU, OF CAMBRIDGE, MASSACHUSETTS, A CORPORATION OF NEW JERSEY.

INTERFITTING CORNER CONSTRUCTION.

Application filed January 28, 1922. Serial No. 532,447.

To all whom it may concern:

Be it known that I, ENOCH OHNSTRAND, a citizen of the United States of America, and resident of Mohawk, in the county of Herkimer and State of New York, have invented new and useful Improvements in Interfitting Corner Constructions, of which the following is a specification.

This invention relates to intermembered corner construction for frames of structures in which great strength and rigidity is desired. It is particularly adapted to vaults, safes, filing cases, and other cabinets which may be subjected to heavy shocks and strains, as for example in a fire.

The above mentioned containers usually have an outer frame of angle iron protecting all edges and corners. Heretofore the corners have ordinarily been constructed by mitering the angle irons, assembling the irons with the mitered edges in contact, and uniting the irons along the mitered edges by welding. Inasmuch as such a corner has but two meeting edges for each angle iron (one for each flange) and no overlapping or interfitting of the parts, it is liable to open up along the welded joint under heavy shock or strain such as frequently occurs during a fire.

Objects of the invention are to produce an improved and strengthened corner construction, to provide interfitting portions on the three angle members at their point of union to make a corner, to provide more than two meeting edges for each angle member, and in general to obviate the weakness of prior corner constructions.

The invention comprises metal bars meeting at a corner and having mutually fitting edges lying in the direction of the bars and mutually fitting edges lying across said direction. The edges are conjoined preferably by a fused metallic joint as by welding. The invention further comprises corner construction for frames constructed of bars in the form of angle irons and a projection upon one iron joined to both flanges of an adjacent iron. The projection may be coplanar with one flange of either of said irons. The projection which is preferably formed by terminating one flange of the angle iron short of the other flange is arranged to extend into a recess complementary thereto in another angle iron. The invention further comprises a frame composed of

three angle irons interconnected together at their ends in angular relationship to each other, each iron having one side terminating short of the other side to form at the end a projection and a recess, each projection fitting in a recess in one of the other irons.

In order to illustrate the invention one concrete embodiment thereof is shown in the accompanying drawing, in which:

Fig. 1 is a perspective view of a safe embodying the features of the invention;

Fig. 2 is an enlarged perspective view of an assembled corner before welding; and

Fig. 3 is a perspective view similar to Fig. 2 after welding.

Fig. 4 is a sectional view on the line 44 of Fig. 2.

The invention is illustrated in connection with a fire resistant cabinet or safe A having an outer frame B of angle iron, double doors C pivoted at D to the frame, lock dial E, and bolt operating handles F.

The particular form of interfitting corner construction chosen to illustrate the invention is best shown in Fig. 2 in which a corner of frame B is shown in perspective prior to welding. Frame B comprises bars or angle irons having flanges 4 and 5. To form a strong interfitting joint one flange of each angle iron is extended beyond the other in the form of a projection or tongue 6. This projection may be produced by cutting away the other flange 4 to the required distance or by making a V-shaped recess therein. The treatment of all of the angle irons is identical. The irons are then assembled as illustrated in Fig. 2, the meeting edges of the flanges lying in the same plane being beveled as indicated at 7 so that the surfaces adjacent all the meeting edges are disposed substantially at an angle of 90°. The angle irons after assembly are tightly clamped in position and are united by welding, preferably with an electric welding machine using a fusible electrode, along the meeting edges, the welding metal completely filling the grooves between the surfaces and joining the parts into a solid integral mass. When the excess metal has been smoothed away no trace whatever of a joint appears as indicated in Fig. 3.

From the foregoing it will be evident that in place of two meeting edges for each angle iron (one on each flange as in the mitered corner of the prior art) at least three meet-

ing edges are produced depending upon the form and arrangement of the interfitting parts. In the embodiment shown each angle iron has four meeting edges. General interengagement of the parts is produced by projection 6 on each angle iron which is made fast to both flanges of an adjacent iron. This interfitting effected by projections received in complementary recesses in adjacent 10 irons together with the welding thereof into an integral structure produces an exceptionally strong corner which effectively resists shocks and strains which the ordinary mitered corner cannot withstand.

15 I claim:

1. Corner construction for frames constructed of angle-irons comprising a projection upon one iron joined to both flanges of an adjacent iron.
- 20 2. Corner construction for frames constructed of angle-irons comprising a projection co-planar with one flange of one iron directly connected to both flanges of an adjacent iron.
- 25 3. Corner construction for frames constructed of angle-irons comprising a projection upon one iron fast to both flanges of a second iron, said projection being co-planar with one flange of said second iron.
- 30 4. Corner construction for angle-iron frames comprising a projection on one iron co-planar with one flange thereof, said projection extending in the plane of one flange of another iron to the other flange thereof, and means uniting the projection to both flanges of said second named iron.
- 35 5. Corner construction for three angle-irons meeting to form a corner comprising a projection upon each iron engaging both flanges of an adjacent iron, the meeting edges of the projections and flanges being integrally united whereby a rigid interfitting corner is formed.
- 40 6. Corner construction for three angle-irons meeting to form a corner and having their flanges collectively disposed in three planes comprising the extension of one flange of each iron to the plane of the flanges perpendicular thereto, the other flange of each iron being recessed to receive in its plane the extension of another iron, the meeting edges of said irons being integrally united.
- 45 7. A frame for cabinets and the like comprising a plurality of angle-irons intercon-

nected together at their ends, each angle-iron having one flange terminating short of the other flange to form a projection and a V-shaped recess at the end thereof, each projection extending into the recess of another angle-iron and being integrally secured thereto along both edges of the V-shaped recess.

8. A frame for cabinets and the like comprising three angle-irons interconnected together at their ends in angular relationship to each other, each angle-iron having a projection extending into a recess in one of the other angle-irons.

9. A frame for cabinets and the like comprising three angle-irons interconnected together at their ends in angular relationship to each other, each angle-iron having a projection extending into a recess in one of the other angle-irons and secured thereto along its edges.

10. A frame for cabinets and the like comprising three angle-irons interconnected together at their ends in angular relationship to each other, each angle-iron having one side terminating short of the other side to form at the end thereof a projection and a recess, and each projection fitting in a recess in one of the other angle irons.

11. A cabinet having angle-irons fitting over the three meeting edges at a corner thereof and overlapping the three sides of the cabinet adjacent the corner, each angle-iron having one flange terminating short of the other flange to form a projection and a recess at the end thereof, the recess of one angle-iron and the projection of another angle-iron being located on each of said three sides in interfitting relationship.

12. A cabinet having angle-irons fitting over the three meeting edges at a corner thereof and overlapping the three sides of the cabinet adjacent the corner, each angle-iron having one flange terminating short of the other flange to form a projection and a V-shaped recess at the end thereof, the recess of one angle-iron and the projection of another angle-iron being located on each of said three sides in interfitting relationship and each projection being secured to its interfitting recess along both edges of the recess.

Signed by me at Mohawk, N. Y., this 24th day of January 1922.

ENOCH OHNSTREND.
